INVENTOR.

CONRAD W. BORGNER,

BY
Franklin S. Dugay

ATTORNEY.

UNITED STATES PATENT OFFICE.

CONRAD W. BORGNER, OF LOWVILLE, NEW YORK.

JOINT FOR SYRINGES AND THE LIKE.

Application filed March 23, 1921. Serial No. 454,698.

To all whom it may concern:

Be it known that I, CONRAD W. BORGNER, a citizen of the United States, residing at Lowville, in the county of Lewis and State 5 of New York, have invented certain new and useful Improvements in Joints for Syringes and the like, of which the following is a specification, reference being had therein to the accompanying drawings.

10 This invention relates to joints or connections, and while especially intended for a joint between the bulb of a syringe and the metallic parts, is obviously not limited to such instrument. An object of the invention 15 is to provide means for securely clamping a yielding member such as a syringe bulb in association with metallic parts of a device such as a barrel or nozzle of a syringe, whereby the parts are maintained in operative relation.

20 A further object of the invention is to provide in combination with a yielding or resilient member, a stud and nozzle, the latter conforming to the configuration of the 25 yielding member with complementary inclined grooves and shoulders adapted to wedgingly clamp the yielding member therebetween when stress is applied for accomplishing such clamping purpose.

30 With these and other objects in view the invention comprises the novel units, elements, parts, combinations and functions as are disclosed in the drawing, together with mechanical equivalents thereof.

35 In the drawings:

Figure 1 is a view of the invention applied to a conventional dentist's syringe shown in side elevation;

Figure 2 is a sectional view through the 40 joint or connection as indicated by line 2-2 of Figure 1;

Figure 3 is a transverse sectional view through the stud and nut, as indicated by line 3-3 of Figure 2, showing the spherical segmental washer in elevation;

Figure 4 is a view in side elevation of the stud, and

Figure 5 is a view in side elevation of a slight modification of the stud.

50 Like characters of reference indicate corresponding parts throughout the several views.

It is well known that a variety of instruments, one of which is represented by a 55 dentist's syringe, provides a collapsible or yielding member and rigid, or metallic

parts by the operation of which fluid is forced from or by the yielding or collapsible member through the rigid or metallic member for various purposes. As shown in 60 the drawings, a bulb 10 is employed substantially spherical in general outlines, but it is to be understood that sphericity is not essential to the present invention and that the shape of the bulb may differ therefrom, and 65 any reference herein to spherical or spheroidal is only intended to be a convenient term to indicate a hollow collapsible bulb.

Associated with the bulb 10 is a barrel 11 which in the particular instance is connected 70 or integral with the nozzle 12. The bulb 10 is provided with an opening through which a stud 13 is inserted, the stud being provided with screw threads which are engaged within the barrel 11, the barrel acting as a 75 nut upon the stud 13. The stud 13 is provided with a head 14 having at the side adjacent the stud an annular groove having walls 15 and 16 inclined to the axis of the stud 13, so that the groove is approximately 80 or substantially V-shaped in cross section radially of said head.

85 A washer 17 is provided having an opening to receive the stud 13 and in the type illustrated is substantially a spherical segment larger in diameter than the head 14 and by reason of its said shape its perimeter overhangs and surrounds said head, said head lying wholly within said washer and stopping short of the base thereof. Its formation as a spherical segment depends upon 90 the sphericity of the bulb 10 and is made to conform to the convexity of such bulb, irrespective of its sphericity. About the central opening which receives the stud 13, an annular shoulder is provided having walls 18 and 19, which in normal relation are parallel to the walls 15 and 16 of the head 14 and therefore also V-shaped in cross section 95 radially of said washer. Owing to the fact that the walls 15 and 16, as well as the walls 18 and 19 are inclined to the axis of the stud 13, it is obvious that by clamping the head 14 and the washer 17 together, an interposed yielding member would be clamped 100 with a wedging action between said complementary walls. The formation of the walls of the groove of the head 14 and of the rib of the washer 17 complementary and inclined is very important to the proper clamping 110 of the yielding member represented by the bulb 10 therebetween.

In operation, it is obvious that the head 14 will be inserted through the opening in the bulb, which is made possible by the elasticity and yielding nature of the bulb itself. The stud 13 will extend outwardly through the opening and the washer 17 will be passed over such extended stud. The barrel 11 will now be engaged upon the stud 13 as a nut and by being screwed down will force the rib of the washer 17 to depress the bulb and compress a portion of the same between the walls of said rib and the walls of the groove of the head 14 to be wedged therebetween by reason of the inclination of said walls. In this manner the bulb 10 is retained in operative association with the metallic parts of the device and the inconvenience of disengagement is overcome.

What I claim to be new is:

- 20 1. The combination of a hollow collapsible ball having an opening of a washer formed substantially as a spherical segment, the interior of which is complementary of the ball, said washer having a perforation coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow.
- 25 2. The combination of a hollow collapsible ball having an opening of a washer formed substantially as a spherical segment, the interior of which is complementary to the ball, said washer having a perforation coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow, said head being contained wholly within the segment and provided about its perimeter with serrations surrounding the furrow.
- 30 3. The combination of a hollow collapsible ball having an opening of a washer formed substantially as a spherical segment, the interior of which is complementary to the ball, said washer having a perforation coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow, said head being contained wholly within the segment and provided about its perimeter with serrations surrounding the furrow.
- 35 4. The combination of a hollow collapsible ball having an opening of a washer formed substantially as a spherical segment, the interior of which is complementary to the ball, said washer having a perforation coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow, said head being contained wholly within the segment and provided about its perimeter with serrations surrounding the furrow.
- 40 5. The combination of a hollow collapsible ball having an opening of a washer formed substantially as a spherical segment, the interior of which is complementary to the ball, said washer having a perforation coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow, said head being contained wholly within the segment and provided about its perimeter with serrations surrounding the furrow.

coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow, said head being contained wholly within the segment.

3. The combination of a hollow collapsible ball having an opening of a washer formed substantially as a spherical segment, the interior of which is complementary to the ball, said washer having a perforation coinciding with the axis of the segment, an annular rib wholly within the segment surrounding the perforation, stopping short of the plane of the base of the washer and V-shaped in cross section on radial lines, a threaded stud inserted through the opening and perforation and having a head within the ball provided with an annular furrow complementary to the annular rib, and a tension nut upon the threaded stud clamping the material of the ball in V-shaped relation between the rib and the furrow, said head being contained wholly within the segment and provided about its perimeter with serrations surrounding the furrow.

In testimony whereof I hereunto affix my signature in presence of two witnesses.

CONRAD W. BORGNER.
